UNITED STATES PATENT OFFICE.

ANTHONY LANZETTA, OF NEW YORK, N. Y.

TORPEDO AND MINE DEFLECTOR.

1,267,672.

Specification of Letters Patent. Patented May 28, 1918.

Application filed September 1, 1917. Serial No. 189,321.

To all whom it may concern:

Be it known that I, ANTHONY LANZETTA, a citizen of the United States, residing at New York city, county of the Bronx, and 5 State of New York, have invented certain new and useful Improvements in Torpedo and Mine Deflectors, of which the following is a specification.

This invention relates to torpedo and 10 mine deflectors as applied to the hulls of ships and marine vessels, and has as its principal object the provision of means adapted to deflect and divert torpedoes and mines directed against or about to strike the ship, 15 in such manner as to prevent damage being done to it.

A further object of my invention is to provide means for enmeshing the torpedo or mine as it strikes a deflector, with little 20 or no danger of causing an explosion thereof, and to utilize the momentum of the torpedo in deflecting or diverting it from the ship.

These and other similar objects are attained by the novel construction and combination of parts hereafter described, and shown in the accompanying drawings forming a material part of this specification, and in which:—

30 Figure 1 is a plan view of the conventional type of ship, partially broken away, and indicating the application of the invention;

Fig. 2 is a fragmental vertical sectional view of the same drawn to an enlarged scale;

Fig. 3 is a top plan view thereof;

Fig. 4 is a perspective view of the net, and,

Fig. 5 is a perspective view of a support 40 plate.

Attached to the sides of the hull of the ship 10, are a plurality of vertically disposed slide-ways or guides 11, containing longitudinal, undercut recesses 12, in which 45 operate rollers 14, engaged with the arms 15, 16, which extend horizontally outward from the hull of the ship, the arms being reinforced by braces 17, the rear ends of which are also provided with rollers movable within the slideways. Each set of arms and braces may be strongly secured together by cross-braces 18.

Attached to the arms near the guides, are

cables 19, by means of which the arms and braces may be raised or lowered to any desired height relative to the deck of the ship, and adjusting the distance to which they may be submerged in the water.

Buoyant bodies 20, which may be conveniently cork, are attached to the arms 15, 60 which aid in holding the deflectors in operative position.

Formed near the outer ends of the arms 16 are eyes 20 and 21, to the latter of which are secured spindles 22, upon which plates 65 32 are pivotally secured, while the eyes 21 serve to support shaft 18, carrying two eyes 42, 44, for the cables 24 of each of the deflector nets.

My deflector nets 25 are formed of steel 70 wire, or other suitable material, of a sufficiently heavy gage to receive the impact of a torpedo, and are of a sufficiently coarse mesh to receive the nose of a torpedo between the wires of the mesh so as, where possible, to avoid imparting a firing impulse to the explosive charge contained in the torpedo head, as the latter strikes the net. These nets are disposed in a substantially vertical plane between the arms 15, 16, and 80 extend lengthwise of the ship.

Plates 32 are used to extend the net, and are hingedly engaged at one end to the spindles 22, while engaged at their opposite ends are floats of cork 33, or the like, 85 by means of which they are partially supported.

The nets 25 are preferably arranged in pairs, between each pair of adjoining arms 16, one end of the net being attached to 90 that end of the plate 32 which engages the spindle 22, then extending upwardly to a point near the arm 15, where it is bent backwardly and downwardly into arcuate form and is carried back to the other end of the 95 plate 32, and then forwardly to a point near the spindle 22, where it engages an iron cable 24, as hereinafter more fully explained.

The nets are bent upon themselves to form 100 two walls, the rearward wall being arcuately formed, while the exterior wall 35 is formed into a plurality of angular bends, the intersection of the angular elements being adapted to receive the impact of a tor- 105pedo.

The peculiar disposition of the net material is such as either to ward off the point of a torpedo or cause the same to be entangled, thereby causing no damage to the ship, and the action of the nets, which are hingedly secured at one end to a support, is such that when a torpedo strikes a net the net swings on its pivotal support and carries the enmeshed torpedo with it, there-
10 by diverting it from its course, and away from the ship.

It will be obvious that the net used may be either single ply, or that several nets, one behind the other, may be employed to form
15 each deflector.

Cables 24 serve to join and hold the two ends of the net together, said cables passing through a tube 40 around which the end 41 of the net is wound, then one end of the
20 cable is passed through the eye 42 on the shaft 23, and up to a tube 43 held in the fold of the net at the extreme point of its height, and then back through the eye 44 on the shaft 23, and from thence back to
25 the tube 40, the ends of the cable being joined.

Knots 45 are formed in each side of the cable so as to act as stops against the eyes 42, 44.

30 The plates 32, and floats 33, are provided with guideways 46 therethrough, through which the end of the net is passed, and the end 41 of the net and the tube 40 also act as a stop to prevent the end of the net from being drawn through the guideways 46.

As a torpedo strikes the net the action of the cable 24 is to pull the two ends of the net toward each other, and thereby serve to enmesh the torpedo, while at the same
40 time the momentum of the torpedo causes the latter to turn the net upon its pivot and deflect the torpedo.

Light cables 47, passing through the tubes 43 may be employed to fasten the upper ends
45 of the nets to the arms 15, or any other suitable fastening means may be used so long as care is used that said fastenings are so constructed that they will break or give away when a torpedo strikes the net.

50 What I claim as new and desire to secure by Letters Patent is:—

1. A torpedo deflector comprising a net pivotally supported at one of its lower ends, and supports therefor, said net being so arranged that when struck by a floating body it will be turned upon its axis at its lower end and deflect said body.
55

2. A torpedo deflector comprising a net pivotally supported at one of its ends, supports therefor, and means operatively engaging the ends of said net to draw said ends toward each other when actuated by striking a floating body.
60

3. A ship defending net having an arcuate

portion and an exterior face presenting a series of alternating projections and indentations, means adapted to distend said net, means for extending said net from a ship, and means for raising and lowering said net.
65

4. A ship defending net having an arcuate portion and an exterior face presenting a series of sharply defined angular edges, a plate adapted to engage and distend said net, means for supporting said net from a ship, and means for holding said net in
70 operative position.
75

5. A torpedo deflector comprising a plurality of meshed nets arranged to form a substantially continuous wall along the ship, said nets being pivotally supported at one of their ends, supports for said nets, and means operatively engaging the ends of said nets to draw the ends thereof toward each other when forcibly struck by a body.
80

6. A torpedo deflector comprising slide-ways secured to the hull of a ship, arms slideable therein, vertically disposed nets pivotally secured to said arms, and cables engaging the ends of said net and adapted to draw said ends toward each other when
85 said net is forcibly struck by a body.
90

7. A torpedo deflector comprising slide-ways secured to the hull of a ship, arms slideable therein, buoyant bodies engaging said arms, nets pivotally secured to said arms,
95 and plates hingedly engaged at the ends of some of said arms and adapted to distend and partially support said nets.
100

8. A torpedo deflector comprising slide-ways secured to the hull of a ship, upper and lower arms slideable in said slideways, floats carried by said upper arms, vertically disposed nets pivotally secured to said lower arms and normally secured to said upper arms, a cable connecting the ends of each
105 net, and hinged plates supported by said lower arms and engaging said nets to distend them.
110

9. A ship defending net comprising an inner curved wall, and an outer wall formed into a plurality of angular bends, supports for said net slidably mounted upon the side of a ship, means for pivotally attaching said net to said supports, and pivoted means engaging said curved wall to distend said net.
115

10. A torpedo deflector comprising slide-ways secured to the hull of a ship, arms slideable therein, buoyant bodies engaging said arms, nets pivotally secured to said arms, plates hingedly engaged at the ends of some of said arms and adapted to distend and partially support said nets, and guideways formed in said plates and adapted to receive said nets.
120

11. A torpedo deflector comprising slide-ways secured to the hull of a ship, arms slideable therein, vertically disposed nets pivotally secured to said arms, cables engaging
125

the ends of said net and adapted to draw said ends toward each other when said net is forcibly struck by a body, and means for limiting the movements of said cables with respect to said net.

In testimony whereof, I have signed my name to this specification in the presence of

two subscribing witnesses, this 8th day of August, 1917.

ANTHONY LANZETTA.
